UNITED STATES PATENT OFFICE.

OSCAR H. FAIRCHILD, OF DENVER, COLORADO, ASSIGNOR OF TWO-THIRDS TO WILLIAM ARCHER DIBOLL, OF DENVER, COLORADO.

REVOLVING FILTER.

No. 872,616.

Specification of Letters Patent.

Patented Dec. 8, 1907.

Application filed April 1, 1907, Serial No. 365,837.

To all whom it may concern:

Be it known that I, OSCAR H. FAIRCHILD, a citizen of the United States of America, residing at the city and county of Denver and 5 State of Colorado, have invented a new and useful Revolving Filter, of which the following is a specification.

My invention relates to improvements in filters; and the objects of my invention are: 10 First, to provide a revolving multiple unit filter. Second, to provide a multiple unit revoluble and automatic sand-cake discharging filter. Third, to provide a simple, durable, and economically operating revoluble 15 filter, that is operated automatically and intermittently to filter slimes ore-pulp solutions for a predetermined portion of its revolution, and expel and discharge the resulting sand-cake during a predetermined part of the 20 remainder of its revolution. I attain these objects by the mechanism illustrated in the accompanying drawings, in which:

Figure 1, is a vertical, longitudinal, sectional view of a revoluble multiple unit filter 25 embodying my invention. Fig. 2, is a plan view of the same. Fig. 3, is a transverse, vertical section of Fig. 1 taken through the supporting shaft. Fig. 4, is an enlarged vertical, sectional view through a portion of the 30 hollow supporting shaft and one of the hollow spokes communicating with the filter frames, and showing the valves which control the communication between the spokes and shaft. Fig. 5, is a plan view of the under side of a pair of the filter boxes detached from the wheel, the filtering material being omitted. Fig. 6, is a sectional view, on line 35 6-6 of Fig. 5. Fig. 7, is an end view of Fig. 5. Fig. 8, is a fragmental, sectional view, 40 showing a modification in the construction of the wheel. Fig. 9, is a front view of Fig. 8. Fig. 10, is a side view of a portion of a wheel, showing a modification in the form of the filter boxes. Fig. 11, is a vertical, sectional view through one of the boxes illustrated in 45 Fig. 10. And Fig. 12, is a view of the bracket supporting the valve trip-pins.

Similar letters of reference refer to similar parts throughout the several views.

Referring to the drawings, the numeral 1, 50 designates a semi-circular receptacle or tank of suitable width, which is preferably constructed of tongue and groove boards, and which is adapted to hold a cyanid or other chemical ore-pulp solution or a solution of

any kind that requires filtering to separate the solution as clear, clean, liquid, from the ore-sand or other material mixed with it. This tank is supported by upper and lower rectangular frames 2 and 3, respectively, 60 which are connected by vertical timbers as shown. Within the tank is rotatably mounted a wheel 4, the rim 5, spokes 6, hub 7, and shaft 8, of which constitute an integral structure. The ends of the shaft 8, are journaled in boxes 9, secured upon the frame 2.

The hub 7, is formed with axial chambers 10 and 11, which are separated from each other by a partition 12, forming an integral part of the hub, and axial bores 13 and 14 extend from these chambers to the outer ends of the shaft. A plurality of threaded holes extend radially from the chambers 10 and 11, through the periphery of the hub, and in these holes are screwed short sections of pipe 75 15. At the base of each spoke, and projecting laterally from opposite sides thereof, are tubular valve housings 16, which as shown are formed integral with the spokes, though they may consist of short sections of pipe which 80 are screwed into openings in the spokes, if desired. The spokes are hollow from end to end to form passage-ways from the valve housings out through the rim of the wheel, and into each valve housing or chamber is 85 screwed a short section of pipe 17, the free end of which is connected to the free end of the adjacent pipe 15, by a union 18. Thus, each spoke is connected with the hub chambers 10 and 11, through the two valve chambers and the pipes 15 and 17. 90

All of the valve chambers on one side of the several spokes, are provided with suitable valves 19, which open or close communication between the spokes and the hub chamber 10, while the valve chambers on the opposite sides of the spokes are provided with similar valves 20, which open or close communication between the spokes and the hub chamber 11. 100

The valves 19 and 20 comprise cylindrical plugs, having ports 21, which extend in axially from the inner end of the plug, and open out at right angles through the periphery of the plug so that when turned to a certain 105 position they either close or open communication between the spokes and hub chambers.

The valves are each provided with a stem 22, which extends out through a cap on the 110

end of the valve chamber, and upon the extremity of each stem a bell crank arm 23 is secured, which is adapted to engage a pair of pins, as the wheel revolves, to first close the valve and then open it at a predetermined point in the wheel's movement. The pins 24 and 25 which operate the valves 19, are secured in a segmental bracket 26, which is attached to the side of the tank and extends 10 in adjacent to the bell crank arms so that the pins will stand in the path of said arms; and the pins 27 and 28, which operate the valves 20, are secured in a similar bracket 29, and these brackets may be provided with a plurality of holes, so that the positions of the pins may be changed to operate the valves at different predetermined points in the movement of the wheel.

Around the periphery of the wheel are secured a number of filter boxes 30, corresponding to the number of spokes in the wheel, and these boxes are arranged in pairs on the rim of the wheel, at the outer end of each spoke, in such manner that they connect 25 through the hollow spoke with the hub chambers 10 and 11. The manner of constructing these boxes is as follows:

Around the rim of the wheel are bolted a number of strips or sections 31, corresponding to the number of spokes, which sections are of a suitable height from the rim of the wheel and preferably of the same width as the rim. The ends of these sections abut, and they are each provided with a port or 35 passage 32, which registers with one of the hollow spokes, said passage being in the form of a T, the upper or horizontal portion of which opens out laterally through each side of the strip. These passages 32, are preferably placed adjacent to the rear ends of the strips, relatively to the direction of movement of the wheel, the purpose of which will appear later.

Transversely across these sections 31, are 45 suitably secured boards 33, which in length are slightly less than the width of the tank 1, and which form the closed sides of the filter boxes. Upon the sides of the sections 31 are secured battens 34, having ports or passages 50 35, registering with the passages 32 of the sections; corresponding battens are secured at the ends and sides of the boards 33, and these battens and the boards form a shallow box on each side of each section 31, which is 55 open on the inner or under side, as will clearly appear by reference to Fig. 5.

The open sides of the boxes are designed to be covered by suitable filtering materials 36, which may consist of, first, wire screen cloth, 60 second, coarse fabric, and third, canvas, though any suitable filtering medium may be employed. In order to hold these materials upon the boxes, the battens forming their edges are cut away to form shouldered off- 65 sets 37, as shown in Figs. 5 and 7, over which

the materials are laid; then a loop or frame 38 of wood or metal is pressed down over the materials so as to confine them between the off-set and the frame (Fig. 6), and the frames are held in place on three sides by clamps 39, 70 or any other suitable means, while at the ends adjoining the sections a wedge 40 may be employed, which is driven in between a bracket 41 and the frame. This manner of securing the filtering materials will permit of their being quickly removed and replaced when necessary. 75

In the end of the bore 13 of the shaft 8, is inserted one end of a pipe 42, the other end of which enters a suitable vacuum tank 43, 80 which is provided with an outlet pipe 44, and with a pipe 45, leading to a suitable vacuum pump, not shown. A stuffing box 46, in the end of the shaft 8, surrounds the pipe 42, and prevents the ingress of air, as the shaft revolves around the pipe. At the opposite end of the shaft, a pipe 47 is inserted, passing through a stuffing box 48, similar to the box 46, and this pipe connects with a source of steam or of air under pressure. To this end 90 of the shaft is keyed a sprocket wheel 49, which connects with a sprocket wheel 50, on a drive shaft 51, on the other end of which is a belt pulley 52, which is connected with a source of power. A chute 53, is secured inside of the tank on each side of the wheel, the lower ends of which discharge through the sides of the tank, while their upper ends extend up beneath the revolving filters to a point where the said filters approach a horizontal position. These chutes are adapted 100 to catch and discharge the cakes composed of fine ore sand which are deposited upon the filters, as the solution is drawn through them into the boxes, and which are thrown off at a predetermined time by the admission into the boxes of steam or of air under pressure, 105 as will presently be more fully explained.

The mechanism above described constitutes the preferred form of my improved revolving filter, but in Figs. 8 and 10 I have illustrated slight modifications of the same. In Fig. 8 the valve housings 16, are dispensed with, and the wheel shaft is provided at each end with a plurality of bores or holes 54, arranged around the main bore, in which the valves 19 and 20 are inserted. The hollow spokes 55 in this form, are arranged in pairs, and while each hollow spoke communicates with both boxes at its outer end, their separate 115 passages do not communicate at the base of the spokes, but open directly into the separate bores 10 and 11. In all other respects, and in the manner of operation, this wheel is similar to the preferred form. 120

In Fig. 10, I have shown still another construction, in which the wheel 56 is made much smaller in diameter, and a series of filter frames or boxes 57 are bolted to its rim, so as to extend in the same direction as the 130

spokes, and not transversely to the rim, as in the preferred form. Each side of these boxes is covered with filtering material, and thus positioned the boxes take up much less lateral space, and may revolve in a narrow tank, while the filtering surface afforded is greatly increased. In other respects this filter is similar to the preferred form.

The operation of the improved filter is as follows: The tank 1, is supplied with cyanid or other chemical ore-pulp solution from a source of supply, and the filter-box-carrying wheel is caused to revolve slowly so that the filter boxes, as they pass successively into the solution, are submerged therein for a period of time sufficient to permit them to be filled with solution. Meanwhile, a vacuum is created in the vacuum tank causing a strong suction through the bore or passage 13, chamber 10, and hollow spokes to the boxes which are wholly or partially submerged, all the valves communicating with which boxes being open. Now, as each spoke approaches and rises beyond a horizontal position, the solution will be drawn from the boxes through the spoke, valve 19, chamber 10, passage 13, and pipe 42 to the vacuum tank 43, the valve 20 on the opposite side of the spoke being closed during this period, and as the spokes communicate with the rear ends of the boxes relatively to the direction of their movement, and the solution falls by gravity into these ends as the wheel revolves, each box or pair of boxes will be thoroughly drained before entering the solution again. Shortly after each pair of boxes pass out of the solution and are emptied, the bell crank arm 23, on the stem of their controlling valve 19, contacts with the trip pin 24, by which the valve is given a quarter turn, and closes communication between the boxes and vacuum tank. As the boxes pass on and over the upper ends of the chutes 53, the bell crank arm on the stem of valve 20, contacts with trip pin 27, by which the valve is opened, and a supply of steam or air under pressure is admitted to the boxes, and the cakes of fine ore-sand and mud which have been caused to adhere to the filters during their passage through the solution, by the vacuum, are thrown off, and fall into the chute, whence they are conveyed without the tank. The valve is soon reversed or closed, by contact with pin 28, and as the boxes again enter the solution, the valve 19 is again opened by contact of its bell crank with pin 25, and the former operation is repeated.

The improved filter is well adapted to the treatment of slimes, which frequently carry a high percentage of value. The solution, after passing through the screens, is clear and clean and subsequently undergoes suitable treatment for the recovery of the values which are in it; one form of treatment being

to pour the solution into a receptacle containing zinc shavings, upon which the gold in the solution is precipitated, the mass being then subjected to heat, causing the gold to form in a button, while the zinc passes off in fumes.

The wheel may be revolved at any practicable degree of speed, and the trip pins for the valves may be set to open and close the valves at any predetermined time. Thus, the filter is automatic in its operation and only requires that the solution in the tank shall be maintained at a level slightly above the axial center of the shaft in order to give satisfactory results.

Having described the invention, what I claim as new and desire to secure by Letters Patent, is:

1. A revoluble filter, comprising a semi-circular solution tank; a wheel mounted in said tank so as to be partially submerged, and having passages which connect on one side with a vacuum tank and on the other side with a source of fluid under pressure; filter boxes on said wheel communicating with said passages, and automatically operated valves for controlling said passages.

2. A revoluble filter, comprising a solution tank; a wheel mounted in said tank so as to be partially submerged, and having hollow spokes communicating with passages in the shaft of said wheel; filter boxes on said wheel communicating with said hollow spokes; a pipe in one end of said shaft leading to a vacuum tank; a pipe in the other end of said shaft leading to a source of fluid under pressure; and automatically operated valves for controlling communication between said spokes and shaft.

3. In a revoluble filter, the combination with a solution tank, of a wheel mounted therein so as to be partially submerged, having a hollow shaft, and hollow spokes communicating therewith, one end of said shaft being connected with a vacuum tank, while the other end is connected with a source of fluid under pressure; filter boxes on said wheel communicating with said hollow spokes, and valves which are automatically operated as the wheel revolves, to open or close communication between the hollow spokes and shaft at any predetermined point in the travel of the wheel.

4. In a revoluble filter, the combination with a semi-circular solution tank, of a wheel mounted therein, having hollow spokes communicating with a hollow shaft and automatically operated valves for controlling communication between the spokes and shaft; filter boxes on said wheel communicating with the hollow spokes; a pipe in one end of the shaft connecting with a vacuum tank; a pipe in the other end of the shaft connecting with a source of fluid under pressure, a partition in said hollow shaft forming

independent passages on each side of its center, and a power-driven wheel on one end of said shaft.

5. In a revoluble filter, the combination with a solution tank, of a wheel mounted thereon so as to be partially submerged therein, having a shaft provided with independent axial passages extending from each end and separated by a central partition, and 10 hollow spokes connecting at their lower ends with the independent passages in the shaft; automatically operated valves on each side of the spokes at their lower ends, which control communication between the spokes and 15 the separate shaft passages; pipes in the ends of the shaft, connecting respectively with a vacuum tank and a source of fluid under pressure; filter boxes secured to the wheel at the extremities of the spokes and communicating with said spokes; and a sprocket wheel on one end of said shaft connected by a chain with a wheel on a power-driven shaft.

6. In a revoluble filter, the combination with a solution tank, of a wheel mounted 25 therein so as to be partially submerged, having a shaft formed with an axial passage extending from each end, separated centrally of the shaft by a partition, and hollow spokes communicating at their lower ends with the 30 separate shaft passages, valves at the lower end of each spoke, filter boxes at the extremities of the spokes and communicating with them, chutes extended to lie beneath the uppermost boxes; pipes in the ends of the 35 shaft, which lead respectively to a vacuum tank and a source of fluid under pressure, and means for automatically opening and closing the valves at any predetermined point in the travel of the wheel.

40 7. In a revoluble filter, the combination with a solution tank, of a wheel mounted therein, having a shaft provided with axial passages separated by a central partition, and hollow spokes connecting at their lower 45 ends with said passages; pipes in the ends of said shaft leading respectively to a vacuum tank and to a source of fluid under pressure; filter boxes extending transversely across the rim of the wheel, and connecting with said 50 hollow spokes; chutes arranged to extend up under the uppermost troughs, and to discharge without the tank, and valves for controlling communication between the spokes and shaft passages, having projecting stems 55 terminating in bell crank arms, and pins arranged in the path of said bell crank arms, by which said valves are opened and closed at predetermined points in the travel of the wheel.

60 8. In a revoluble filter, the combination with a solution tank of a wheel mounted therein, having hollow spokes, and a shaft having an axial passage extending in from each end to a dividing partition, one of said 65 passages being connected with a vacuum

tank, while the other is connected with a source of fluid under pressure, valve housings extending from each side of the base of the several hubs, having axial valve chambers which intersect the hollow of the hub; 70 pipes connecting the valve housings with the shaft passages; cylindrical plug valves in said housings which control communication between the spokes and shaft, having projecting stems terminating in bell crank arms, pins arranged in the path of said arms for operating the valves, and filter boxes on the rim of the wheel communicating with the hollow spokes. 75

9. In a revoluble filter, the combination with a solution tank of a wheel mounted to stand partially within said tank, having a pair of axial chambers in its hub separated by a partition, and passages extending from said chambers to the ends of a supporting 80 shaft integral with the hub, one of which connects with a vacuum tank and the other with a source of fluid under pressure, said chambers being provided with radial holes extending through the hub; hollow spokes 90 having cylindrical valve casings extending from opposite sides of their lower ends; pipes extending from the radial holes of the hub chambers and connected with the valve casings; valves in said casings for controlling 95 communication between the hollow spokes and chambers, having projecting stems terminating in bell crank arms, pins adjustably secured in a bracket for operating the valves at predetermined points in the wheel's movement; filter boxes arranged transversely across the rim of the wheel, and communicating with the hollow spokes, and a chute on each side of the wheel extended adjacent to the under side of the uppermost boxes, and 100 arranged to discharge without the tank.

10. In a revolving filter, the combination with a solution tank, of a wheel having hollow spokes communicating with independent axial passages in a supporting shaft, one of 110 which is arranged to connect with a vacuum tank and the other with a source of fluid under pressure; filter boxes on the rim of said wheel communicating with the hollow spokes and valves automatically operated 115 at predetermined points in the travel of the wheel, for opening or closing communication between the spokes and shaft passage.

11. In a revoluble filter, the combination with a wheel, comprising a shaft having independent axial passages terminating in chambers which are separated by a partition, said 120 passages connecting respectively with a vacuum tank, and a source of fluid under pressure, hollow spokes, and filter boxes at the ends of said spokes arranged in pairs which communicate with each other and with the spoke, of means for automatically opening and closing communication between the said chambers and hollow spokes, at predeter- 130

mined times, comprising valves arranged on opposite sides of the spokes, having extended stems which terminate in bell crank arms, and pins adjustably secured in the path of the bell crank arms.

12. In a revoluble filter, the combination with a wheel comprising a shaft, having independent axial passages terminating in chambers which are separated by a partition, said passages connecting respectively with a vacuum tank, and a source of fluid under pressure, and hollow spokes communicating with said chambers, of filter boxes arranged in pairs at the extremity of each spoke,

which communicate with each other and 15 with the spoke, filtering material on the inner side of each box, and means for detachably securing said material to the box, and automatically operated valves for opening or closing communication between the spokes 20 and shaft passages at predetermined points in the travel of the wheel.

In testimony whereof I affix my signature in presence of two witnesses.

OSCAR H. FAIRCHILD.
